(57) **CLAIM**

The ornamental design for a computer stand, as shown and described.

DESCRIPTION

FIG. 1 is a perspective view of a computer stand showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the computer stand where the computer stand is in a configuration of use; and,

FIG. 10 is a perspective view of the computer stand where the computer stand is in another configuration of use. The broken lines in the drawings depict portions of the computer stand that form no part of the claimed design.
